CLAIM

The ornamental design for a fluid applicator as shown and described.

DESCRIPTION

FIG. 1 is a perspective view of our ornamental design for a fluid applicator.

FIG. 2 is another perspective view of our ornamental design.

FIG. 3 is a perspective view of our ornamental design for a fluid applicator.

FIG. 4 is another perspective view of our ornamental design.

FIG. 5 is a top view of our design shown in FIG. 1.

FIG. 6 is a side plan view of our ornamental design shown in FIG. 1.

FIG. 7 is another side plan view of our ornamental design shown in FIG. 1.

FIG. 8 is a bottom view of our ornamental design shown in FIG. 1; and,

FIG. 9 is another side plan view of our ornamental design shown in FIG. 1.

The use of broken lines indicates that the portion of the article depicted in broken lines forms no part of the design and is not to indicate the relative importance of parts of a design.
